(57) CLAIM

The ornamental design for a compact, as shown and described.

DESCRIPTION

FIG. 1 is a perspective view of a compact showing my new design;

FIG. 2 is a front elevation view;

FIG. 3 is a rear elevation view;

FIG. 4 is a left side view;

FIG. 5 is a right side view;

FIG. 6 is a top plan view; and,

FIG. 7 is a bottom plan view.

In the drawings, the broken lines illustrate portions of the article which form no part of the claimed design.
